UNITED STATES PATENT OFFICE.

ANTONIO CURRENTE, OF WEST NEW YORK, NEW JERSEY.

CLAMPING DEVICE.

Application filed July 23, 1924. Serial No. 727,692.

To all whom it may concern:

Be it known that I, ANTONIO CURRENTE, a citizen of the United States of America, residing at West New York, county of Hudson, State of New Jersey, have invented a new and useful Clamping Device, of which the following is a specification.

My invention relates to clamps and is especially suitable in clamping forms for concrete columns.

The main object of the invention is to provide a clamp which may be quickly applied to forms of various sizes whether of square or other cross-section, and means for quickly and easily tightening the clamp and for holding it in place.

Another object is to provide a more or less unitary clamp from which there are no parts to get lost, so that the clamp will always be ready for use.

Fig. 1 is a perspective of a pair of clamps constructed according to the invention holding a form for a concrete column.

Fig. 2 is a fragmentary sectional view on a larger scale of the parts shown in Fig. 1, and

Fig. 3 is a perspective of a key for tightening the clamps against the form.

Each clamp consists of two long thin metal strips 1 and 2 pivotally connected near their ends as by the pin or rivet 3. The strips 1 and 2 are each perforated throughout their length by one or more rows of equally spaced holes 4. Preferably two rows of holes in staggered relationship are provided, the holes being somewhat closer together than shown in the drawings so as to give a fine adjustment to the size of the form or other object to be clamped. The clamps are shown attached to a form consisting of four separate sides 5 of approximately equal width, such as would be used for a column of square cross-section, but it will be obvious that forms of other cross-section could be clamped equally well. A lug 6 of strip stock similar to that composing the strips 1 and 2 has the laterally offset portions 7 and 8. The portion 8 is made just long enough to provide a firm supporting surface for attachment to one of the strips 1 or 2 and has perforations capable of registering with those in either of the strips. The offset of lug 6 is approximately equal to the thickness of the strips so that the strip 1 and lug portion 7 of one clamp may readily receive the strip 2 of

another clamp. While the lug may be of about the same length as the strips and permanently secured to one of them, for economy of manufacture I prefer to make it considerably shorter than the strips and to removably connect it to its strip as by the bolts and nuts 9. When it is desired to use the clamps on forms for different sized columns the lugs may be detached and reset in accordance with the size of the forms to be clamped.

In clamping the forms two lugs are first secured preferably one to each strip 1 of two clamps, but in some cases it may be desirable to secure lugs to both strips of the same clamp and to omit lugs from the other clamp or even to omit the lugs entirely. The sides of the form are next assembled and two clamps set to embrace opposite corners of the form, one strip of each clamp extending through the bifurcation formed by the lug on the cooperating strip of the other clamp. To tighten the clamps I provide a key comprising as shown in Fig. 3 a long arm 10 and a short curved arm 11 with a pin 12 extending through the junction of the two arms and a rounded portion 13 at the end of the arm 11. I curve the short arm 11 so that the pin 12 may be inserted in a perforation in one of the strips somewhat removed from the edge of the crossing strip thus leaving the nearest perforation 14 unobstructed by the key. Pulling arm 10 in the direction indicated by the arrow in Figure 2 will tighten the clamp against the form 5 to any desired degree until some hole such as 14 is just clear of the strip 1. To hold the tightened clamp in position I provide two tapered pins 15 and 16, one of which may be inserted through the first perforation in each strip beyond the edge of the intersecting strip. When lug 6 is used one of the pins passes through registering perforations in both the lug and its associated strip. I prefer to yieldably but permanently secure the pins 15 and 16 as by a chain 18 to a flange 17 on the free end of lug 6 so that the pins will always be at hand when the clamps are to be placed on a form.

The purpose of extending the pin 12 and pressure member 13 in both directions from the body of the key is to permit the key to be applied to the strip from above or below and with either face next to the strip as may be more convenient.

Clamps constructed according to my in-

vention are obviously very cheap to manufacture, can be made strong and light, have no parts to wear out, and none to get lost so that quick erection and taking down of forms is assured. Various changes in details may of course be made without departing from the scope of my invention.

I claim:

1. A clamp for forms and the like comprising two pivotally connected strips, each having a number of spaced transverse holes therethrough, and a lug carried by one of the strips and having offset ends, each supplied with holes to register with those in the strip so that one of said ends may be attached to one of said strips by means passing through registering holes and thereby positioning the other end along the adjacent strip with the corresponding holes in register and spaced from the strip sufficiently for another strip to be placed therebetween.
2. A clamp for forms and the like comprising two strips of suitable length loosely connected together at their ends and each having a plurality of rows of spaced staggered perforations, a lug having two approximately parallel portions offset from each other the thickness of one of said strips, both portions having perforations to register with those in the strips and one portion being bolted to one of the strips, and a pair of pins to fit the perforations and having flexible connections with the lug.
3. A clamp for forms and the like comprising two strips of approximately equal length loosely riveted together at their ends

and each having two rows of equally spaced staggered perforations, a lug having two approximately parallel portions laterally offset from each other, both portions having perforations to register with those in the strips and one portion being bolted to one of the strips, and a pair of tapered pins to fit the perforations and chained to the lug.

4. In a device of the character described, two clamps each comprising two pivotally connected perforated strips, and a key to tighten said clamps, said key comprising a lever having a long arm, a fulcrum pin to fit the perforations in the strips extending through the lever and a short curved arm terminating in a transverse member, extending to opposite sides of the lever adapting it for use with a strip of either clamp to engage a strip of the other clamp placed on either side thereof said transverse member having a pressure face approximately parallel to the fulcrum pin.

5. In a device of the character described two clamps each comprising two pivotally connected perforated strips one of the strips of one of said clamps having a bifurcated portion to receive a strip of the other clamp, a key to tighten said clamp comprising a lever having a long arm, a fulcrum pin to fit the perforations in the strips and extending through the lever and a short curved arm terminating in a member extending to opposite sides of the short curved arm to engage both parts of the bifurcated strip of the other clamp.

ANTONIO CURRENTE.
